UNITED STATES PATENT OFFICE.

WEEDEN B. UNDERWOOD, OF ROCHESTER, NEW YORK, ASSIGNOR TO WILMOT CASTLE COMPANY, OF ROCHESTER, NEW YORK, A CORPORATION.

ELECTRICALLY-HEATED VESSEL.

1,192,477.

Specification of Letters Patent.

Patented July 25, 1916.

Application filed December 14, 1915. Serial No. 66,822.

To all whom it may concern:

Be it known that I, WEEDEN B. UNDERWOOD, a citizen of the United States, and resident of Rochester, in the county of Monroe and State of New York, have invented certain new and useful Improvements in Electrically-Heated Vessels, of which the following is a specification.

This invention relates to vessels in which water or other fluids are heated by electrical means, and particularly to vessels used as sterilizers for surgical instruments. In vessels of the kind in question it has been common to employ automatic means for breaking the electric circuit, by which the heating-elements are energized, upon the attainment of a dangerous temperature, such as might occur in case the water is allowed to evaporate entirely from the vessel.

This invention relates particularly to such automatic devices, and one object of the invention is to produce an arrangement in which a fusible member is employed, for the purpose in question, in a novel and simple manner, having particular regard to accessibility and convenient renewal of the fusible member, and to the use of a member of simple and inexpensive form.

Another object of the invention is to provide for inclosing the circuit-breaker and all other parts of the automatic device in question, except that part which is necessarily accessible for the purpose of renewing the fusible member.

Other objects of the invention, and the features of construction by which the various objects are attained, will be set forth hereinafter, in connection with the following description of the illustrated embodiment of the invention.

In the accompanying drawings: Figure 1 is a front-elevation of a water-boiler or sterilizer embodying the present invention, shown partly in vertical section; Fig. 2 is a bottom-view of a part of the sterilizer, with the bottom of the casing removed; Fig. 3 is a plan-view of a part of the sterilizer, with the cover removed; and Fig. 4 is a vertical sectional view, on a larger scale than the preceding figures, showing the automatic heat-controlled circuit-breaker in open-circuit position.

The invention is illustrated as embodied in

a sterilizer having a vessel or body which comprises side-walls 5, a flat bottom 6, and a removable cover 7.

The receptacle is heated by a plurality of flat, elongated, electric heating-units 8, of any ordinary or suitable form, which lie directly against the lower surface of the bottom 6. The heating-units are held in place by means of a plate 9 beneath them, and screws 10 are passed through openings in the plate and in the bottom 6, and are threaded into a rigid metal frame 11, which lies on the upper surface of the bottom 6.

The frame 11, in addition to constituting a part of the means for clamping the heating-units against the bottom 6, acts also to divide the space immediately above the bottom 6 so as to provide pockets 12. Since these pockets lie directly above that part of the bottom which is in contact with the heating-units, if the user fails to replenish the water in the sterilizer, that part of the water which is in these pockets will be first evaporated, so that the pockets become dry while there is still enough water remaining in the exterior space to prevent injury to the soldered joint between the bottom 6 and the side-walls 5. The temperature of that part of the bottom within the pockets will rise, however, at this time above the boiling-point of the water, and advantage is taken of this fact to automatically break the electric circuit and interrupt the action of the heating-units before the water is entirely exhausted from the sterilizer.

For the foregoing purpose a circuit-breaker is employed comprising fixed contact-springs 13 and pivotally mounted contact-springs 14. The springs 13 are mounted on, but insulated from, a bracket 15 fixed to and depending from the plate 9, and the springs are connected to binding-posts 16 by which they may be connected, in turn, with one terminal of a source of electric current. The contact-springs 14 are mounted on, but insulated from, a bar 17 which has pivots 18 formed at its ends, and these pivots engage holes in brackets 19 fixed to and depending from the plate 9. Each contact-spring 14 is connected by a flexible conductor 20 with one terminal of one of the heating-units 8, the other terminals of the unit being connected, by a con-

necter 21, with a binding-post 22 through which connections may be made with the external source of current.

The heat-controlled device comprises a hollow post 23, of which the upper end is fixed in the bottom 6 by means of a cap-nut 24. A plunger 25 is arranged to slide within the post, and a compression-spring 26, inclosed within the post, bears downwardly on this plunger. The fusible member is in the form of a shearing-pin 27, which engages perforations in the post and plunger and normally retains them in the position shown in Fig. 1.

15 The post and the plunger are longitudinally slotted, to receive a flat arm 28 which extends from the bar 17. This arm, in turn, is slotted to receive a pin 29 which passes transversely through the upper end of the plunger. In the upward position of the plunger the parts are held so that the contact-springs are in engagement. When the bottom 6 becomes overheated, however, the heat is conducted down the post to the shearing-pin, and when the predetermined temperature is reached this pin is melted, whereupon the spring 26, assisted by the force of gravity, moves the plunger and the arm 28 downwardly, thus separating the contact-springs, as shown in Fig. 4, and breaking the circuit through the heating-units.

It is desirable to have the electrical devices inclosed safe from dust, or from interference or injury, while at the same time having the fusible member conveniently accessible for replacement when necessary. The arrangement above described lends itself conveniently to such inclosure. As shown in the drawings, the sides 5 and the bottom of the body of the vessel are extended downwardly to form the sides 30 of a casing, and this casing is closed at the bottom by a plate 31. The post and the plunger extend downwardly through an opening in the plate 31, so that they are always accessible for the purpose of resetting the circuit-breaker, but all of the other parts of the circuit-controlling mechanism are inclosed within the casing. The vessel is supported upon legs 32, so as to raise the post and the

plunger clear of the surface on which the vessel rests.

My invention is not limited to the embodiment thereof hereinbefore described and illustrated in the accompanying drawings, 55 but it may be embodied in various other forms within the nature of the invention as it is defined in the following claims.

I claim:—

1. The combination, with a heating-unit, 60 of a circuit-breaker connected therewith, and means for controlling the latter, comprising a hollow post adapted to engage the heated body, a plunger slideable in the post, and connected with the circuit-breaker, and a fusible shear-pin normally connecting the plunger and the post and preventing relative movement thereof.

2. A circuit-breaker comprising a hollow post adapted to engage a heated body, a 70 plunger slideable in the post, and connected with the circuit-breaker, and a fusible shear-pin normally connecting the plunger and the post, preventing relative movement thereof and adapted to receive heat from the heated 75 body through the hollow post.

3. In an electrically-heated vessel, the combination, with the body of the vessel, and a heating-unit attached thereto, of a circuit-breaker connected with the heating-unit; and means, for controlling the circuit-breaker, comprising a hollow post engaging the body of the vessel, a plunger slideable in the post, and connected with the circuit-breaker, and a fusible shear-pin normally 85 connecting the plunger and the post and preventing relative movement thereof.

4. In an electrically-heated vessel, a circuit-breaker comprising a fixed contact-member and a pivoted contact-member; a 90 hollow post adapted for connection, at one end, with the heated body of the vessel; a plunger movable in the post; a spring inclosed in the post and engaging the plunger; a fusible shear-pin connecting the post and 95 the plunger and normally preventing movement of the latter; and pin-and-slot connections between the plunger and the pivoted contact-member.

WEEDEN B. UNDERWOOD.
